METHOD FOR REJUVENATING USED SELF LOCKING NUTS

Bobby J. Hansen, Box 114, Surfside Colony, Calif.
Filed Sept. 9, 1957, Ser. No. 682,824
1 Claim. (Cl. 29—401)

This invention relates to new and improved apparatus and method for rejuvenating used, self-locking nuts.

A large number of different types of self-locking nuts have been developed in the past. At the present time, self-locking nuts which are built so as to include a center-nut-like portion having a threaded opening extending therethrough, a flange extending from one side of the center nut-like portion around the opening, and an elastomeric member held around this opening under compression by this flange, are widely used for a variety of purposes. These nuts are considered very efficient as initially used, and appear to be replacing various conventional and older types of self-locking nuts for a number of different purposes.

Self-locking nuts of the type described in the preceding paragraph, however, suffer from certain inherent disadvantages. After these nuts have been used for a long period, the elastomeric members employed in them tend to fail to exert a desired locking action against a threaded member such as, for example, a common bolt. Although a number of theories have been advanced as to why these elastomeric members fail to exercise their desired function after a prolonged period, it is believed that no one completely has the answer to this problem.

It can be theorized that the elastomeric members used in self-locking nuts of the type indicated in the preceding discussion, fail to exercise their desired function after prolonged periods due to the surface areas of these elastomeric members which engage threaded members failing or deteriorating because of chemical reasons, or because of mechanical disruption through repeated engagement with threaded surfaces. Both of these theories are at least theoretically acceptable. It is well known that elastomeric materials such as, for example, various rubber compositions, will tend to deteriorate at their surfaces, so as to not retain their inherent initial properties. It is also well known that threads will tend to cut into various elastomeric materials to varying extents. Indeed, many types of constructions are based upon the ability of threads to be cut into certain elastomeric materials. It is also possible that self-locking nuts of the type indicated may fail to exercise a desired holding action after prolonged use because of the flanges used on these nuts to hold these elastomeric members yielding to some extent.

An object of the present invention is to provide a new and improved method for treating used self-locking nuts of the type described so as to return these nuts to substantially their initial effectiveness.

Because of the nature of this invention, it is not considered necessary or expedient to set forth in further detail a long list of various objects and advantages of the invention. Such other objects and advantages of the invention will be fully apparent to those skilled in the art to which this invention pertains from a detailed consideration of the remainder of this description, including the appended claims and the accompanying drawing in which:

FIG. 1 is a side elevational view of a used, self-locking nut capable of being rejuvenated in accordance with this invention;

FIG. 2 is a cross-sectional view taken at line 2—2 of FIG. 1;

FIG. 3 is a cross-sectional view, similar to FIG. 2, of

2

self-locking nut shown in the preceding figures which has been treated according to this invention;

FIG. 4 is a perspective view of a die used in accordance with this invention in rejuvenating used, self-locking nuts; and

FIG. 5 is a diagrammatic view showing the use of this die, this figure showing the die in section along line 5—5 of FIG. 4.

In all figures of the drawing like numerals are used to designate like parts wherever convenient for purposes of illustration and explanation. It is to be understood that this invention is capable of being used with self-locking nuts having a different appearance than the appearance of the self-locking nuts illustrated. Similarly, it is to be understood that the basic principles of this invention can be employed with differently appearing dies which are specifically designed so as to be used with various types of self-locking nuts.

As an aid to understanding this invention it may be stated that it concerns the rejuvenation of used, self-locking nuts, each of which nuts is formed so as to include a center nut-like portion having a threaded opening extending therethrough, a flange extending from one side of the center nut-like portion around the opening, and a ring-like elastomeric member held around the opening on this side by this flange against the center nut-like portion so as to be held under compression. In accordance with the method of this invention, such nuts are treated so that the flanges employed in them are bent toward the center nut-like portion around the opening in order to change the compression on these elastomeric members, and so as to extend these members toward the centers of these openings so that these elastomeric members may efficiently serve the purpose of holding the complete self-locking nuts in place against threaded members passing through these nuts. The apparatus of this invention involves die means as will hereinafter be described for use in bending such flanges.

In FIG. 1 of the drawing there is shown a used, self-locking nut 10 of the type which is specifically adapted to be treated in accordance with this disclosure. This nut 10 includes a center nut-like portion 12 having a threaded opening 14 extending therethrough. On a side 16 of this center nut-like portion 12 there extends a ring-like curved flange 18 which serves to define between this flange and the side 16 of the nut-like portion 12 a ring-like internal cavity 20 within which a ring-like elastomeric member 22 is held under compression. This elastomeric member 22 may be formed out of a wide variety of materials, such as, for example, various rubber compositions, various polyurethane resins, polychloroprene or the like.

In a used, self-locking nut, such as the self-locking nut 10, as shown in FIGS. 1 and 2 of the drawing, the elastomeric member possesses a surface 24 constituting an extension of the opening 14, and this surface 24 is of a generally "enlarged" variety so that the elastomeric member 22 cannot resiliently hold a bolt or the like extending through the opening 14. Normally the elastomeric member 22 is held under compression through the use of the flange 18. If desired, this flange 18 may be provided with slots 26, so as to subdivide it into a plurality of fingers, each of which fingers engages the elastomeric member 22.

In order to rejuvenate this self-locking nut 10, it is considered necessary to bend the flange 18 so that this flange 18 exerts compression upon the elastomeric member 22 in order to force the surface 24 of this elastomeric member to a configuration, such as indicated in FIG. 3 of the drawing. As previously indicated in this figure there is shown in cross-sectional view the self-locking nut 10 treated or after being rejuvenated in accordance

with the teachings of this disclosure. It is noted that the surface 24 of this rejuvenated nut extends a short distance from the actual interior surface of the opening 14 so as to be capable of resiliently engaging a threaded member, such as, for example, a bolt.

The nut 10 is placed in the configuration shown in FIG. 3 through the use of a die 30 such as indicated in FIG. 4 of the drawing. This die is provided with at least one opening or cavity 32, which has a top portion 34 which is shaped to the exterior shape of the nut-like portion 12 of the self-locking nut 10, but which is shorter than this nut 10. This top portion 34 terminates in an internal flange 36 which is adapted to receive the portion of the side 16 of a nut 10 between the flange 18 and this nut-like portion 12. The cavity 32 also has a bottom section 38 which corresponds in shape to the shape of the flange 18 finally desired when the self-locking nut 10 is rejuvenated as shown in FIG. 3. If desired, any number of cavities such as cavity 32 may be placed within the die 30.

In using this die 30 it is located as shown between a fixed platen 40 and a movable platen 42 on any sort of a convenient hydraulic press or the equivalent. Next, the nut 10 as shown in FIG. 5 is placed within the die 30 in the obvious manner, and the platens 40 and 42 are caused to move against one another so as to apply force in a lengthwise direction corresponding to the direction of the axis of the opening 14 in order to compress this nut and deform the flange 18 the desired amount, and so as to extend the surface 24 of the elastomeric member 22 being treated to a necessary extent so that this elastomeric member 22 of the nut 10 is capable of holding a threaded member with the force that it was initially capable of exerting.

By this type of treatment, the elastomeric members within self-locking nuts of the type described are not only pushed slightly toward the centers of openings within these nuts, but these elastomeric members are deformed slightly from their initial configurations so that different portions of these elastomeric members are, it is theorized, placed so as to be engaged by different portions of threaded members than previously. Also, by virtue of this process, the elastomeric members 22 tend to be extended within the nuts treated to a certain extent, and it is believed or theorized that the surface portions 45 of these nuts are moved slightly so that the interior por-

tions of these elastomeric members which probably are unharmed by oxidation or other like aging influences can be effectively used in exercising a locking action.

Because of the nature of this invention and the fact 5 that it is capable of wide modification, it is considered as being limited only by the appended claim forming a part of this disclosure.

I claim:

A method for rejuvenating a used, self-locking nut, 10 said nut being formed so as to include a center nut-like portion having a threaded opening extending therethrough, a flange extending from one side of said center nut-like portion around said opening, and an elastomeric member held around said opening on said side by said flange against said center nut-like portion under compression, said elastomeric member having a surface constituting a continuation of said opening, which surface is designed to resiliently engage a threaded member extending through said opening so as to lock said threaded member in place, said used self-locking nut being characterized by said elastomeric member no longer presenting an effective surface for engaging and holding a threaded member extending through said opening, which method comprises: applying force to said flange around said opening so as to bend said flange toward said center nut-like portion around said opening, said bending of said flange serving to change the compression on said elastomeric member so as to deform said elastomeric member slightly in such a manner as to extend said elastomeric member toward the center of said opening so that said surface of said elastomeric member is capable of efficiently holding a threaded member extending through said opening.
